ELECTRONIC SCANNING DEVICE

Juichi Osawa, Tokyo, Japan, assignor to International Standard Electric Corporation, New York, N. Y., a corporation of Delaware

Application June 5, 1936, Serial No. 83,669
In Japan August 3, 1935

6 Claims. (Cl. 178—7.2)

This invention relates to scanning of the kind employed in television or similar systems and more particularly to electronic beam scanning.

The object of this invention is to provide an improved device for the transmission of images utilizing an electronic beam scanning means.

In television or similar systems requiring electronic scanning, certain methods have been used heretofore, an example of which is a method in which the electron generating source in a Braun tube is used as a photoelectric plane, the photoelectrons generated therefrom being accelerated in a proper direction and the photoelectrons radiated from elemental areas thereof being projected upon an electron collector in succession, and the current generated thereby being amplified and transmitted. Another method heretofore used involves the use of a photoelectric plane composed of a large number of minute photoelectric elements, said elements being scanned by the electron current in the Braun tube, discharge being effected in succession between said minute photoelectric elements and a metallic plate provided oppositely and capacitively to said elements, and the discharging current which is generated at that time being transmitted as an output.

In the device of this invention as hereinafter described as an illustrative embodiment, a means is provided in a vessel which is so arranged that it successively sets up a space charge when it is scanned by an electron means, a control electrode having a plurality of minute elements which are photoelectrically sensitive is arranged so that it lies in an operative position with respect to said charge, the control electrode is illuminated by the image light from a body, and the potential which is to be generated due to the difference in illumination of each minute element controls the space current due to the space charge which is successively generated as above described. As the potential upon each minute photoelectric element is changed corresponding to the brightness of each part of the object, the current which is to be controlled by said potential is caused to form an image current proportional to the illumination at any given time of each part of the image plane due to the scanning of the radiated electron current.

A feature of the device of this invention lies in the fact that the energy necessary for the image control is almost zero, as only a balancing potential is utilized. The scanning efficiency of this device is made entirely independent of the number of picture elements constituting the im-

age and the number of repetitions of the image. Also, in the device of this invention, as there is no sudden bombardment of electrons upon the acting surface which is photoelectrically sensitive, as is the case in the so-call iconoscope, there is no probability of causing the breakdown of the photoelectric plane, and as it is not of the nature which utilizes a transient phenomenon, it has an advantage in that it is possible to obtain an image having less distortion.

The invention will be more readily understood by referring to the following description taken in connection with the accompanying drawing forming a part thereof, in which:

Fig. 1 is an arrangement of the device of this invention; and

Figs. 2, 3 and 4 show a number of practical types of an opposed electrode and a control electrode.

Referring more particularly to the drawing, Fig. 1 shows a practical example of the device of this invention. In the figure, 1 is a cathode which generates an electron current, 2 is a flux collecting electrode which serves to concentrate and project the electron flux into an opposed electrode 6 by means of devising battery 13, 3 is an accelerating anode having a small hole in the center, 4, 4 are the deflecting plates for producing scanning, and 5 is a vessel which maintains the electrode in vacuum. The electron current emitted by the cathode 1 is concentrated and projected into a point upon the opposed electrode 6, its position being made to change by the action of the two sets of deflecting plates which cause the electrode 6 to be scanned in the well-known manner.

The opposed electrode 6 is a metal sheet made of, for example, aluminum having a thickness of the order of a few microns. The electrons of high speed which have been emitted from 1 are allowed to shoot electrode 6 which lessens their speed to practically zero so that the electrons just manage to pass through plate 6 where they form a space charge in the rear thereof. The element 7 is a grid shaped control electrode which has a surface composed of minute pieces of photoelectric material insulated from each other, for example, it has the construction shown in Fig. 2.

With reference to Fig. 2, 16 is a conductor, 17 an insulating film, and 18 a layer of photoelectric material arranged at fixed intervals upon 17, such as, for example, a thin film of caesium mounted upon a silver foil. The central conductor 16 is maintained at a definite potential by a suitable

means, such as the battery 25. When light is projected upon the elemental pieces 18 of the electrode 7, these pieces radiate photoelectrons, and the potential of these pieces will be brought up until it becomes almost equal to the maximum point of potential of the electrode 6 lying in the neighborhood thereof. The potential which is finally reached at each elemental point depends upon the amount of the radiation of the photoelectrons and hence it is proportional to the illumination of the light and is higher as the light intensity becomes greater. Moreover, said potential depends upon the radiation of photoelectrons and the influence of the leakage path at that portion as well as the potential distribution of each electrode, and it is not influenced by the increase or decrease of the number of image points. When the potential of the conductor 18 is taken properly the potential of the photoelectric pieces 18 becomes negative with respect to plate 6. Electrons emitted from the cathode 1 shoot at the plate 6, and the electrons of low speed which appear from the rear of said plate are thus not caused to bombard the small pieces 18.

In cooperation with the control electrode 7, an anode net 8 is provided in a position on the opposite side of electrode 7 with respect to electrode 6. When a suitable potential is given to the anode 8, one portion of the electrons emitted from the plate 6 reaches the electrode 8, forming there a space current which flows into the output circuit, thereby causing a potential drop across the resistance 19 in said circuit.

Thus, when a strong electron current strikes at a point of the plate 6, an electron current of low speed is radiated from a point of the same position at the rear of said plate, which causes a current to be produced in the output circuit. The rays of light from the image plane are projected upon the plane of control electrode 7 by means of a lens 9. The plate 6 is placed close to the electrode 7 and the scanning is done by the electron current as mentioned above.

The space current and hence the current of the output circuit is caused to successively change its value according to the magnitude of potential of each photoelectric piece 18 upon the control electrode 7, or in other words, the current of the output circuit is to be controlled by the potentials of each photoelectric piece which is changed from time to time and hence by the illumination of each point of electrode 7. As the difference of potential at each point is caused to vary according to its change in illumination, it is clear that the change of said current is sensitive to the change of illumination.

As the output current is produced continuously in proportion to the illumination at each point of the image which had been projected upon the electrode 7, this output current may be amplified, if desired, and transmitted into a transmission circuit.

The constructions and actions of the control electrode and the opposed electrode of this invention shown in Fig. 3 will now be explained. It is possible to have them operate similar to that above described by arranging it so as to put a net shaped member 20 instead of the opposed electrode plate 6 in Fig. 1, to give a proper negative potential to said member and to dampen the electrons of high speed which had been emitted from the cathode 1 and accelerated by the accelerating anode 3, said net shaped member 20 thereby changing said electrons into a space

charge in the neighborhood of each point of the control electrode 7.

The device shown in Fig. 4 is an example of a construction using the plate 6 and the electrode 7 of Fig. 1 in combination. In this figure, a core 21 is covered with an insulating substance 22 upon which a photoelectric substance 23 is applied at suitable intervals only at one side surface and a potential is given to the core 21. This arrangement permits the suppression of the striking electron current and performs the control of the space charge by the photoelectric potential of the photoelectric spot 23.

Although it is not specifically shown in the drawing, the plate 6 may be made of a substance which is especially susceptible to secondary electron radiation, such as for example, a sheet of aluminum which had been properly treated. With this arrangement a concentrated electron current which has the most suitable speed for secondary electron radiation is transmitted from the cathode 1 which bombards the plate 6 to produce a sufficient space charge due to the secondary electrons, the primary electrons being caused not to pass through the metallic plate in this case.

Various other modifications may obviously be made without departing from the spirit of the invention, the scope of the invention being defined by the appended claims.

30. What is claimed is:

1. An arrangement for the transmission of images comprising an electron scanning device having means for generating a moving beam of electrons, an electrode of thin sheet metal interposed in the path of said moving beam, an anode, the thickness of said sheet metal being so small that, as a result of said moving stream of electrons striking one side of said sheet metal, a stream of electrons passes from the other side of 35 said sheet of metal to said anode, photoelectric means for controlling the flow of electrons between said electrode first mentioned and said anode, and an output circuit interconnected between said electrode and said anode.

2. A cathode ray tube having an envelope, a separating member adapted to emit secondary electrons dividing said envelope into two chambers, the first chamber containing means for producing a cathode ray beam and means for causing the cathode ray beam to scan said separating member, the second chamber containing a photo-sensitive member and an anode and means responsive to projection of light upon said photo-sensitive member for causing the secondary electrons emitted by the separating member to be modulated by the change on the photo-sensitive member.

3. Cathode beam scanning means for a television camera, comprising an evacuated vessel containing a plate-like element having an extended surface capable of emitting electrons, a second plate-like element having a photo-emissive surface coating, spaced a small distance from said first surface and parallel thereto, means for projecting an image of an object on said coating to cause emission of electrons therefrom and thereby place different charges upon different elemental areas respectively of said second element, whereby a free electron emitted from said first surface into said space will travel toward said second surface under control of said charges, and means for causing electrons to be emitted into said space from said first surface element by element thereof in succession.

4. Cathode beam scanning means according to

claim 3, wherein said second plate-like element comprised an apertured screen, said photo-emissive coating being on the surface of said screen remote from said extended surface whereby electrons emitted from said first surface travel through said apertures of said screen in accordance with the said charges.

5. Cathode beam scanning means according to claim 3, wherein said means for causing electrons to be emitted comprises means for scanning said first plate-like element to produce secondary electron from said element.

6. Cathode beam scanning means according to claim 3, wherein said second plate-like element comprised an apertured screen, said photo-emissive coating being on the surface of said screen remote from said extended surface whereby electrons emitted from said first surface travel through said apertures of said screen in accordance with the said charges, wherein said means for causing electrons to be emitted comprises means for scanning said first plate-like element to produce secondary electron from said element.
